CLAIM

The ornamental design for cove and pin template segments, as shown and described.

DESCRIPTION

FIG. 1 is a right front perspective view of cove and pin template segments;

FIG. 2 is a front view of the cove and pin templates shown in FIG. 1;

FIG. 3 is a left-side view of the cove and pin templates shown in FIGS. 1 and 2

FIG. 4 is a right-side view of the cove and pin templates shown in FIGS. 1-3;

FIG. 5 is a rear view of the cove and pin templates shown in FIGS. 1-4;

FIG. 6 is a top view of the cove and pin templates shown in FIGS. 1-5;

FIG. 7 is a bottom view of the cove and pin templates shown in FIGS. 1-6;

FIG. 8 is a right front perspective view of an alternate configuration of the cove and pin template segments;

FIG. 9 is a right front perspective view of the cove and pin template segments shown in FIG. 8;

FIG. 10 is a right-side cross-section view of the cove and pin template segments of FIG. 9;

FIG. 11 is a right front perspective cross-section view of the cove and pin template segments of FIG. 10;

FIG. 12 is a right-side cross-section view of the cove and pin template segments of FIG. 9; and,

FIG. 13 is a right front perspective cross-section view of the cove and pin template segments of FIG. 12.
